UNITED STATES PATENT OFFICE

CECIL M. WICKSTRUM, OF OMAHA, NEBRASKA

CANOPY

Application filed December 20, 1929. Serial No. 415,588.

This invention relates to a flower arbor or protecting canopy, the primary object of the invention being to provide novel means to be placed over new graves to protect the flowers against the elements, to the end that the flowers will be maintained in a fresh condition.

An important object of the invention is to provide a device of this character which may be readily and easily assembled or dismantled without the use of tools.

Another important object of the invention is to provide a device of this character which may be folded into a small and compact article to permit the device to be stored with facility.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

Referring to the drawings:

Figure 1 is a side elevational view of a flower arbor constructed in accordance with the invention.

Figure 2 is a plan view thereof, a portion of the top being broken away.

Figure 3 is an enlarged fragmental elevational view of the top of the canopy, showing the connection between the top bars and corner posts of the canopy.

Figure 4 is a sectional view taken on line 4-4 of Figure 3.

Figure 5 is a longitudinal sectional view through the socket members.

Figure 6 is a sectional view taken on line 6-6 of Figure 3.

Referring to the drawings in detail, the device comprises supporting posts 5 which have pointed lower extremities so that they may be readily driven into the ground surface. At the upper end of each of these posts is a head 6 defining an annular shoulder 7.

The reference character 8 designates a pair of pivotally connected socket members, the

socket members being of shapes to receive the inner ends of the bars 9 which are constructed of flexible wood such as hickory, so that the bars may bend, lending a curved-like appearance to the top of the canopy.

At the outer end of each bar 9, is a downwardly extended arm 10, which arm is provided with a laterally extended portion 11 formed with a cut out portion to permit the laterally extended portion to be fitted against the post 5 associated therewith. The top of the arbor or roof, embodies a length of canvas material rectangular in formation, the same being provided with a finishing fringe 12 that extends downwardly from the body portion. The top or roof is so constructed that it may be stretched tightly over the roof bars, the bow of the roof bars being such as to exert a pressure on the roof section or top to hold the roof section or top in position.

As clearly shown by Figure 6 of the drawings, lengths of fabric materials are secured to the under surface of the top or roof in such a way as to provide pockets 13, to receive the bars 9 and hold the bars in position.

From the foregoing it will be obvious that due to the construction shown and described, the bars 9 may be readily and easily removed or replaced and the device folded into a small and compact article for storing or transportation.

The reference character 8 designates a pair of pivotally connected socket members, the socket members being of shapes to receive the inner ends of the bars 9 which are constructed of flexible wood such as hickory so that the bars may bend, lending a curved roof-like appearance to the top of the arbor.

At the outer end of each bar 9, is a downwardly extended arm 10, which arm is provided with a laterally extended portion 11 formed with a cut out portion to permit the laterally extended portion to be fitted against the post 5 associated therewith. The top of the arbor or roof, embodies a length of canvas material rectangular in formation, the same being provided with a finishing fringe 12 that extends downwardly from the body portion. The top or roof is so constructed that it may be stretched tightly over the roof bars,

the bow of the roof bars being such as to exert a pressure on the roof section or top to hold the roof section or top in position.

As shown by the drawings, strips of fabric material 13 are secured to the under surface of the top of the arbor, the strips being arranged in spaced relation with each other defining pockets for the reception of the outer ends of the bars 9 to the end that the bars 9 will be secured to the top or roof. When the top or roof is wet and partially shrunk, it is obvious that the ends of the bars 9 may be positioned in certain of the pockets to cause the roof to be stretched taut.

From the foregoing it will be obvious that due to the construction shown and described, the bars 9 may be readily and easily removed or replaced and the device folded into a small and compact article for storing or transportation.

I claim:

1. A device of the class described comprising corner posts, flexible bars, means at the ends of the bars for removably securing the bars to the corner posts, a flexible covering positioned over the bars and upper ends of the posts, and said covering engaging the posts at the upper ends thereof to hold the upper ends of the posts against lateral movement, and said covering adapted to hold the bars in bowed positions.

2. A device of the class described comprising corner posts, flexible bars, means at the ends of the flexible bars for removably securing the bars to the corner posts, and a covering of flexible material to be stretched over the bars to bow the bars.

3. A device of the class described comprising corner posts, flexible roof bars, downwardly extended arms secured to the bars adjacent to the free ends thereof, said arms having cut out portions to fit around the corner posts and hold the bars against movement with respect to the corner posts, and a covering positioned over the bars.

4. A device of the class described comprising corner posts, flexible roof bars, arms connected with the roof bars, means at the upper ends of the posts to restrict vertical movement of the arms, and a covering of fabric material positioned over the roof bars.

5. A device of the class described comprising corner posts, flexible roof bars, pivotally connected socket members, said roof bars having their inner ends positioned in the socket members, means at the outer ends of the roof bars for removably securing the roof bars to the corner posts, and a covering of fabric material stretched over the roof bars.

6. A device of the class described comprising corner posts, flexible roof bars, socket members for connecting the inner ends of the roof bars, said roof bars being longer than the diagonal distance between corner posts to cause the roof bars to bow, means for

securing the roof bars to the corner posts, and a covering of fabric material adapted to be stretched over the roof bars.

In testimony that I claim the foregoing as my own, I have hereto affixed my signature.

CECIL M. WICKSTRUM.
